UNITED STATES PATENT OFFICE

WALTER M. COOK, OF LUDLOW, VERMONT, ASSIGNOR TO INTERNATIONAL COMBUSTION
ENGINEERING CORPORATION, OF NEW YORK, N. Y., A CORPORATION OF DELAWARE

MECHANICAL SEPARATOR

Application filed December 23, 1929. Serial No. 416,050.

This invention relates to certain new and useful improvements in mechanical separators, and more particularly to improvements in that type of separator in which the finely divided material to be graded is projected, preferably by centrifugal force, across the path of a rising air current which picks up and carries away in suspension only the finer particles, whereas the heavier particles gravitate out of the air stream into a collecting means.

This invention contemplates an improved means for insuring the separation, from the rising air stream, of all of the heavier particles of material. To accomplish this result a rotary deflecting member or "whizzer" is mounted on a central vertical axis within the separation chamber and above the distributor so as to cut across the annular rising air stream. This rotary deflector comprises a multiplicity of substantially radial blades or vanes the central portions of which are connected by an apron or covering plate so that air passages remain only between the outer portions of the vanes. The outer ends of the vanes closely abut a conical deflecting member that extends upwardly and inwardly so as to overlap the outer ends of the vanes. The rotating vanes throw any heavier particles of the material that may tend to rise in the air stream, outwardly against the inclined lower surface of the deflecting ring from which they carom downwardly at the sides of the chamber and join the heavier material that initially gravitates out when thrown from the distributor. The only material that can rise above these cooperating deflecting members is sufficiently fine to be carried in suspension in the rising air stream which finds its way between the rapidly rotating deflector blades.

Above the deflecting members, and between them and the fan which actuates the rising air stream, is an inwardly extending annular partition wall which compels the air laden with finely divided material to flow inwardly, or counter to the outward throw imparted by centrifugal force to the material in the rotating air stream before it enters the fan chamber. This permits a final action

of centrifugal force on any relatively heavy particles that may find their way up into this inwardly flowing portion of the air stream, these heavier particles being thrown outwardly to a ledge above the fixed conical deflector ring from which they fall back through the rotary deflector. 55

The general object of this invention is to provide an improved separator of the type briefly described hereinabove and disclosed 60 more in detail in the specifications which follow.

Another object is to provide an improved deflecting means for an air separator adapted to cooperate with a revolving impeller for 65 forcing heavier material particles out of the air stream.

Another object is to provide adjustable means for forcing the air stream to follow a circuitous path in opposition to the path in 70 which material particles are impelled by centrifugal force.

Another object is to provide an improved deflecting means comprising a revolving member having a closed central portion and 75 an outer portion consisting of a multiplicity of radial vanes with intervening air spaces, in combination with a deflector ring partially overlapping the outer end portions of the vanes in opposition to the path of air-flow 80 between the vanes.

Other objects and advantages of this invention will be more apparent from the following detailed description of one improved form of apparatus constructed according to 85 the principles of this invention.

In the accompanying drawings:

Fig. 1 is an elevation of the improved separator, the right-hand portion being shown in 90 central vertical section.

Fig. 2 is a central vertical section through the upper portion of the separator on a larger scale.

Fig. 3 is a plan view, the lower portion being broken away substantially on the line 95 3-3 of Fig. 1.

Fig. 4 is an inverted horizontal section, taken substantially on the line 4-4 of Fig. 1.

Fig. 5 is a partial vertical section showing a modified form of deflector. 100

Fig. 6 is another partial vertical section showing a modified mounting for the stationary deflector.

The separator housing comprises a suitably supported outer casing consisting of a top wall 1, an upper cylindrical shell 2, and a lower conical shell 3 converging to the bottom discharge opening 4 through which the finely divided material separated out by this air separation process is delivered. An inner casing, positioned symmetrically about the same central vertical axis as the outer casing but spaced inwardly therefrom comprises an upper annular cover plate 5, an upper cylindrical shell 6, and a lower downwardly converging conical portion consisting of the two overlapping conical shells 7 and 8. A discharge spout 9 leads out through one side of the outer conical shell 3 so as to discharge the heavier particles collected by the inner conical shell 8. The inner shell construction is spaced from the outer casing by means of a plurality of spaced radial brace members 10 or other suitable struts or supports.

The movable portion of the separator comprises a rotating assembly mounted on the central shaft 11 which is positioned to rotate about the central vertical axis of the separator housing. The upper portion of this shaft 11 has a bearing at 12 in the sleeve 13 formed on the bearing plate 14 mounted centrally in the top wall 1 of the housing. The lower section of a gear casing 15 is formed on bearing sleeve 13, and the upper section 16 of this gear case carries a roller bearing 17 in which the upper end portion 18 of shaft 11 is journaled. A bevel gear 19 is keyed on the upper portion of shaft 11 and meshes with and is driven by the bevel pinion 20 keyed on the inner end of drive shaft 21, supported in bearings 22 and 23 on the top of the housing and driven from any outside source of power in any suitable manner as by means of the gear or pulley indicated at 24. A downwardly projecting bearing sleeve 25 secured to plate 14 carries the roller thrust bearing 26 in which the intermediate portion of shaft 11 is journaled, and a suitable packing means indicated at 27 serves to keep dust or finely divided material from the separator from working its way into the bearings.

A spider 28 secured to the lower portion of shaft 11 serves to support the circular horizontal distributing plate 29, and a hollow rotatable housing consisting of the lower cylindrical member 30 and the upper downwardly converging conical member 31. A spout 32 mounted in cover plate 1 projects downwardly into the upper rotating conical housing 31, and the ground or pulverized material that is to be separated is poured in through spout 32 from which it passes through the rotating housing members 31 and 30 and is deposited on the rapidly rotating distributing disc 29

from which it is thrown outwardly by centrifugal force through the open radial passages 33. A fan consisting of a plurality of radially extending blades 34 carried externally by the upper rotating conical housing 31 serves to keep up a circulation of air within the separator housing as indicated by the arrows in Fig. 1, there being a rising air current within the upper portion of the inner casing, and an outwardly and downwardly flowing air current in the space between the inner and outer casings, the air current passing back into the inner casing through a plurality of openings 35 between the overlapping upper and lower inner conical casing members 7 and 8.

As is usual in separators of this type, the material introduced through spout 32 and thrown outwardly by the centrifugal distributing plate 29 is diffused across this rising air current within the inner casing. Only the lighter and finer particles are carried upwardly by the rising air current created by fan 34, the heavier materials gravitating downwardly through the inner casing and being collected by the lower cone 8 and discharged through outlet pipe or spout 9. This initial separation process is not sufficient to completely withdraw all of the heavier particles of material and secure the desired grade of fineness in the material eventually discharged by fan 34 into the outer casing, and the particular improvements of this invention relate to novel means, positioned between the distributing disc 29 and fan 34, for removing more completely the heavier material particles from the rising air stream.

A rotary deflector or "whizzer" comprises a multiplicity of rather long narrow blades or vanes 36 anchored at their inner ends as at 37 to the rotary cylindrical casing member 30 and extending outwardly along radial lines toward the cylindrical shell 6 of the inner casing. A great number of these vanes 36 may be used, the number depending upon several factors such as the speed of rotation of the rotatable assembly, the diameter of the rotatable deflector and somewhat on the degree of fineness required in the separation process. Preferably there will be more than eight of these blades 36, and a great many more may be used. Cooperating with this rotary deflector is an annular stationary deflector carried by the surrounding inner walls of shell 6, this deflector comprising an upwardly and inwardly extending conical shell 38 and an inwardly extending horizontal ring or flange 39 which overlap the outer end portions of the vanes 36. The outer ends of the vanes 36 (in the form shown in Figs. 1 to 4 inclusive) are beveled inwardly and upwardly as indicated at 40 so as to extend closely adjacent the inner wall of conical deflector 38. The inner portions of the vanes or blades 36 are covered by and connected by

5 a plate or apron 41, positioned in substantially the same horizontal plane as the annular flange 39 of the stationary deflector, leaving only a plurality of openings 42 between the outer portions of the vanes 36 through which the rising air current may pass.

10 Positioned on the annular top plate 5 of the inner shell is an inwardly adjustable annular partition comprising a plurality of similar overlapping plates 43 adapted to be separately adjusted inwardly or outwardly by means of the rods 44 which may have their outer ends threaded as at 45 and engaged in nuts 46. Fixed guide pins 47 mounted in supporting ring 5 project through guide slots 48 adjacent the edges of each pair of overlapping plates, whereby the plates are held in place and are permitted individual adjustment inwardly and outwardly. The purpose of this partition, which comprises an adjustable inward extension of the cover plate or ring 5, is to cause the air stream after passing through the passages 25 42 in the rotary deflector to flow inwardly toward the center of the separator before passing upwardly through annular space 49 into the fan chamber 50. By making the inner diameter of the partition adjustable, 30 the rate of air flow may be regulated.

In operation, the material deposited on the rapidly rotating distributing plate 29 will be thrown outwardly by centrifugal force, as already described, and the heavier 35 particles will immediately settle out, only the lighter material being carried upwardly by the rising air stream towards the rapidly rotating deflector 36. As soon as the heavier particles in this rising air stream are caught 40 by the revolving blades 36 they will be carried around by these blades and thrown outwardly by centrifugal force against the under surface of the stationary deflector 38, 39 from which they will be thrown downwardly 45 to joint the other heavier particles that have already separated out and are collected in the inner cones 7 and 8 and discharged through spout 9. The central apron 41 prevents the 50 passage of any materials through the inner portions of the rotating blades which are not traveling at as great a linear speed, and the only material that is carried above these co-operating deflector members is the very fine material that may be carried in the air stream 55 passing through spaces 42 between the outer portions of the vanes 36.

It will be noted that after this air stream has passed above the deflector members just described, it is compelled by the annular partition consisting of cover plate 5 and adjustable plate 43, to flow inwardly or toward the center of the separator, and in opposition to the centrifugal force applied to the suspended material in the whirling air stream, before 60 passing upwardly through annular space 49

into the fan chamber. The result is that any relatively heavy particles that may possibly find their way upwardly through the passages 42 in the rotary deflector will be thrown outwardly by centrifugal force from this inwardly flowing air stream and will be deposited as indicated at 51 above the stationary deflector 39, 40, from which position they will gradually dribble or settle back through the rotary deflector by means of which they are thrown against the lower surface of the stationary deflector plate 38 and thence are thrown down so as to settle out with the heavier particles, as already described. 70

75 In the alternative construction shown in Fig. 6, the deflector cone 38 is supported from the casing 6 by any suitable type of brackets or struts 54, so that a narrow annular space 55 remains between the outer lower edge of the cone and casing 6. The heavier material 80 thrown above the cone 38 by centrifugal force will settle down through passage 55 into the inner collecting cone. 85

90 The result is that only the very finest material is carried up by the air stream into the fan chamber and thence thrown out by the fan through upper passage 52 and down through annular passage 53 between the inner and outer casings. This fine material will to a large extent settle out from the 95 slowly moving air stream and will be collected by the lower outer cone 3 and discharged through opening 4 at the bottom thereof. The air stream flows back through passage 35 into the inner casing and thence upwardly 100 through inner cone 7 to carry more fine material in suspension upwardly through the separating devices.

105 In the modification shown in Fig. 5, the outer conical deflector 56 and inwardly extending flange 57 (corresponding to the parts 38, 39 previously described) are carried by the outer end portions of the rotating deflector vanes 36, instead of by the fixed casing 6. A small annular clearance space 58 will remain between the lower outer edge of conical deflector 56 and the inner wall of casing 6. 110

115 The operation of this form of the invention is essentially the same as that of the first described apparatus. The material thrown outwardly by the rotating vanes 36 will be deflected downwardly by the conical deflector 56, which is also rotating in this form of the invention. Material that is thrown out above the deflecting members will settle back 120 through the narrow passage 58 between conical deflector 56 and casing 6, as in the apparatus shown in Fig. 5.

125 Applicant is aware that rotary impact members or deflectors have heretofore been used to throw the heavier particles of the material out of the rising air stream, but he believes that he is the first to use such a deflector in combination with a conical deflector projecting inwardly and upwardly over the 130

outer ends of the rotary deflector blades and in close proximity thereto, so that the material thrown outwardly by the rotary deflector is positively caught and deflected downwardly and absolutely prevented from being carried upwardly by the rising air stream. The only rising air currents in which material may be carried in suspension pass directly between the rapidly rotating blades of the deflector between the rotary apron 41 and the deflector ring 39. Furthermore, the material that passes through this separation process is subsequently subjected to a second centrifugal separation process by causing the air stream to flow inwardly in opposition to centrifugal force, the action of this force being here sufficient to throw out any heavier materials that may by chance pass above the cooperating deflector members, as already described hereinabove.

I claim:

1. In a separator comprising a casing, a rotary distributing member therein, and means for causing an upward air flow in the casing, a rotary deflector positioned above the distributor, and an annular deflector cooperating with and overlapping the outer portion of the rotary deflector for throwing material downwardly within the casing.

2. In a separator comprising a casing, a rotary distributing member therein, and means for causing an upward air flow in the casing, a rotary deflector positioned above the distributor, and an annular stationary deflector carried by the casing and overlapping the circumferential portion of the rotary deflector.

3. In a separator comprising a casing, a rotary distributing member therein, and means for causing an upward air flow in the casing, a rotary deflector positioned above the distributor, and an annular stationary deflector carried by the casing and overlapping the circumferential portion of the rotary deflector, there being an annular series of passages through the outer portion of the rotary deflector adjacent the stationary deflector.

4. In a separator comprising a casing, a rotary distributing member therein, and means for causing an upward air flow in the casing, a rotary deflector positioned above the distributor, and an annular stationary deflector carried by the casing and comprising an upwardly and inwardly inclined conical portion overlapping the outer portion of the rotary deflector.

5. In a separator comprising a casing, a rotary distributing member therein, and means for causing an upward air flow in the casing, a rotary deflector positioned above the distributor, said deflector comprising a multiplicity of substantially radially extending vanes, and an annular conical deflector extending inwardly and upwardly over the ends

of the vanes and adjacent the inner wall of the casing.

6. In a separator comprising a casing, a rotary distributing member therein, and means for causing an upward air flow in the casing, a rotary deflector positioned above the distributor, said deflector comprising a multiplicity of substantially radially extending vanes, and an annular stationary deflector carried by the casing and including an inwardly extending flange overlapping the outer ends of the rotary vanes.

7. In a separator comprising a casing, a rotary distributing member therein, and means for causing an upward air flow in the casing, a rotary deflector positioned above the distributor, said deflector comprising a multiplicity of substantially radially extending vanes with their outer ends beveled inwardly and upwardly, and an annular conical deflector carried by the casing and projecting inwardly above the beveled end portions of the vanes.

8. In a separator comprising a casing, a rotary distributing member therein, and means for causing an upward air flow in the casing, a rotary deflector positioned above the distributor, said deflector comprising a multiplicity of substantially radially extending vanes with their outer ends beveled inwardly and upwardly, and an annular conical deflector carried by the casing and projecting inwardly above the beveled end portions of the vanes, there being an inwardly extending flange projecting from the smaller end of the cone over the upper outer portions of the vanes.

9. In a separator comprising a casing, a rotary distributing member therein, and means for causing an upward air flow in the casing, cooperating closely overlapping relatively movable deflecting members positioned above the distributing member for throwing heavy particles of material outwardly and then deflecting them downwardly within the casing.

10. In a separator comprising a casing, a rotary distributing member therein, and means for causing an upward air flow in the casing, a rotary deflector positioned above the distributor, and non-rotary means positioned above and beyond the outer edge portion of the rotary deflector but closely adjacent thereto for deflecting material downwardly within the casing.

11. In a separator, comprising a casing, a rotary distributing member therein, and means for causing an upward air flow in the casing, a rotary deflector positioned above the distributor, said deflector comprising a multiplicity of substantially radially extending vanes, a substantially circular apron connecting the inner portions of the vanes so that passages remain only between the outer portions thereof, and an annular conical deflector extending inwardly and upwardly over

the outer ends of the rotary vanes and extending closely adjacent the inner wall of the casing.

12. In a separator comprising a casing, a rotary distributing member therein, and means for causing an upward air flow in the casing, a rotary deflector positioned above the distributor, said deflector comprising a multiplicity of substantially radially extending vanes, a substantially circular apron connecting the inner portions of the vanes so that passages remain only between the outer portions thereof, the outer ends of the vanes being beveled inwardly and upwardly, and an annular conical deflector carried by the casing and projecting inwardly above the beveled end portions of the vanes.

13. In a separator comprising a casing, a rotary distributing member therein, and means for causing an upward air flow in the casing, a rotary deflector positioned above the distributor, said deflector comprising a multiplicity of substantially radially extending vanes, a substantially circular apron connecting the inner portions of the vanes so that passages remain only between the outer portions thereof, the outer ends of the vanes being beveled inwardly and upwardly, and an annular conical deflector carried by the casing and projecting inwardly above the beveled end portions of the vanes, there being an inwardly extending flange projecting from the smaller end of the cone over the upper outer portions of the vanes.

14. A separator comprising an inner casing having a conical lower collecting portion, a similarly shaped outer casing surrounding the inner casing in spaced relation thereto, the upper portion of the inner casing housing a separating chamber, a rotary assembly positioned centrally within the casings and comprising a lower distributing disc and an upper fan for causing an air circulation upwardly through the inner casing and downwardly through the outer casing, means for feeding material to be separated to the disc, a rotary deflector mounted on the rotary assembly between the distributing disc and fan and projecting outwardly adjacent the wall of the inner casing, and an inwardly and upwardly projecting conical deflector carried by the inner casing and overlapping the outer portion of the rotary deflector.

15. A separator comprising an inner casing having a conical lower collecting portion, a similarly shaped outer casing surrounding the inner casing in spaced relation thereto, the upper portion of the inner casing housing a separating chamber, a rotary assembly positioned centrally within the casings and comprising a lower distributing disc and an upper fan for causing an air circulation upwardly through the inner casing and downwardly through the outer casing, means for feeding material to be separated to the disc, a rotary deflector

mounted on the rotary assembly between the distributing disc and fan and projecting outwardly adjacent the wall of the inner casing, said deflector comprising a multiplicity of substantially radially extending vanes the outer ends of which are beveled upwardly and inwardly, and an inwardly and upwardly projecting conical deflector carried by the inner casing and overlapping the beveled ends of the vanes.

16. A separator comprising an inner casing having a conical lower collecting portion, a similarly shaped outer casing surrounding the inner casing in spaced relation thereto, the upper portion of the inner casing housing a separating chamber, a rotary assembly positioned centrally within the casings and comprising a lower distributing disc and an upper fan for causing an air circulation upwardly through the inner casing and downwardly through the outer casing, means for feeding material to be separated to the disc, a rotary deflector mounted on the rotary assembly between the distributing disc and fan and projecting outwardly adjacent the wall of the inner casing, said deflector comprising a multiplicity of substantially radially extending vanes the outer ends of which are beveled upwardly and inwardly, a circular apron connecting the inner portions of the vanes, and an inwardly and upwardly projecting conical deflector carried by the inner cone and overlapping the beveled ends of the vanes.

17. A separator comprising an inner casing having a conical lower collecting portion, a similarly shaped outer casing surrounding the inner casing in spaced relation thereto, the upper portion of the inner casing housing a separating chamber, a rotary assembly positioned centrally within the casings and comprising a lower distributing disc and an upper fan for causing an air circulation upwardly through the inner casing and downwardly through the outer casing, means for feeding material to be separated to the disc, a rotary deflector mounted on the rotary assembly between the distributing disc and fan and projecting outwardly adjacent the wall of the inner casing, said deflector comprising a multiplicity of substantially radially extending vanes, the outer ends of which are beveled upwardly and inwardly, a circular apron connecting the inner portions of the vanes, and an inwardly and upwardly projecting conical deflector carried by the inner cone and overlapping the beveled ends of the vanes.

18. A separator comprising an inner casing having a conical lower collecting por-

- tion, a similarly shaped outer casing surrounding the inner casing in spaced relation thereto, the upper portion of the inner casing housing a separating chamber, a 5 rotary assembly positioned centrally within the casings and comprising a lower distributing disc and an upper fan for causing an air circulation upwardly through the inner casing and downwardly through the outer casing, means for feeding material to be separated to the disc, a rotary deflector mounted on the rotary assembly between the distributing disc and fan and projecting outwardly adjacent the wall of the inner 10 casing, said deflector comprising a multiplicity of substantially radially extending vanes, the outer ends of which are beveled upwardly and inwardly, a circular apron connecting the inner portions of the vanes, and an 15 inwardly and upwardly projecting conical deflector carried by the inner cone and overlapping the beveled ends of the vanes, and an annular deflecting partition projecting inwardly over the apron between the deflector 20 and fan to compel an inwardly directed air flow above the defectors in opposition to the 25 centrifugal force of the rotating parts.
19. A separator comprising an inner casing having a conical lower collecting portion, a similarly shaped outer casing surrounding the inner casing in spaced relation thereto, the upper portion of the inner casing housing a separating chamber, a rotary assembly positioned centrally within 30 the casings and comprising a lower distributing disc and an upper fan for causing an air circulation upwardly through the inner casing and downwardly through the outer casing, means for feeding material to be 35 separated to the disc, a rotary deflector mounted on the rotary assembly between the distributing disc and fan and projecting outwardly adjacent the wall of the inner casing, said deflector comprising a multiplicity 40 of substantially radially extending vanes, the outer ends of which are beveled upwardly and inwardly, a circular apron connecting the inner portions of the vanes, and an 45 inwardly and upwardly projecting conical deflector carried by the inner cone and overlapping the beveled ends of the vanes, and an 50 annular deflecting partition comprising a plurality of radially adjustable overlapping plates whereby the inner diameter of 55 the partition can be adjusted in size projecting inwardly over the apron between the defectors and fan to compel an inwardly directed air flow above the defectors in opposition to the 60 centrifugal force of the rotating parts.
20. A separator comprising an inner casing having a conical lower collecting portion, a similarly shaped outer casing surrounding the inner casing in spaced relation thereto, the upper portion of the in- 65
- ner casing housing a separating chamber, a rotary assembly positioned centrally within the casings and comprising a lower distributing disc and an upper fan for causing an air circulation upwardly through the inner casing and downwardly through the outer casing, means for feeding material to be separated to the disc, and a plurality of overlapping rotary and stationary deflectors carried by the rotating assembly and inner cone respectively and positioned between the distributing disc and fan for compelling the upwardly flowing air to follow a circuitous path.
21. In a separator comprising a casing, a rotary distributing member therein, and means for causing an upward air flow in the casing, a rotary deflector positioned above the distributor, said deflector comprising a multiplicity of substantially radially extending vanes, and an annular conical deflector mounted on the end portions of the vanes and extending inwardly and upwardly over these end portions, the lower outer edge of the conical deflector extending into close proximity to the inner wall of the casing.
